(57) CLAIM

The ornamental design for an audible signal for alarms, as shown.

DESCRIPTION

FIG. 1 is a perspective view of the front and top of an audible signal for alarms showing my new design, with the broken line showing for illustrative purposes only and forming no part of the claimed design;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.
